VACUUM CLEANER

Carl E. Meyerhoefer, Brooklyn, N. Y., and Jack Fairchild Fleming, Summit, N. J., assignors to Lewyt Corporation, Brooklyn, N. Y., a corporation of New York

Application May 11, 1954, Serial No. 30,413

Term of patent 14 years

(Cl. D9—2)

To all whom it may concern:

Be it known that we, Carl E. Meyerhoefer and Jack Fairchild Fleming, citizens of the United States, residing at Brooklyn, county of Kings, and State of New York, and Summit, county of Union, and State of New Jersey, respectively, have invented a new, original, and ornamental Design for a Vacuum Cleaner, of which the following is a specification, reference being had to the accompanying drawing, forming a part thereof, wherein:

Fig. 1 is a top plan view of a vacuum cleaner showing our new design;

Fig. 2 is a side elevation thereof;

Fig. 3 is a bottom plan view;

Fig. 4 is a front view; and
Fig. 5 is a rear view.

We claim:
The ornamental design for a vacuum cleaner, as shown.
